POP-UP TOY

Philip A. Derham, Audubon, Pa., assignor to Wilkening Manufacturing Company, Philadelphia, Pa., a corporation of Delaware

Application February 1, 1957, Serial No. 637,796

1 Claim. (Cl. 46—146)

The present invention relates generally to children's 15 toys and more particularly to toys of the so-called jack-in-box pop-up type.

An object of the present invention is to provide a new and useful children's toy which is simple and inexpensive to produce, rugged and resistant to breaking, and entertaining in mode of operation. Another object of the present invention is to provide a jack-in-box pop-up toy in which the lid or cover is mounted directly upon the movable pop-up element (as distinguished from the hinged lids customarily employed). Still another object of this invention is to provide a jack-in-box pop-up toy wherein the outer case or housing is of deformable material adapted to be manually squeezed to effect release of the pop-up element. A further object of the present invention is to provide a jack-in-box pop-up toy wherein the spring-mounted pop-up element is maintained in angular position when enclosed within its outer case or housing, so that, upon release, it springs up in a novel gyrating manner.

Other objects and advantages of the present invention are apparent in the following detailed description, appended claim and accompanying drawings.

For the purpose of illustrating this invention, there is shown in the accompanying drawings one form thereof which is presently preferred; it being understood, however, that the different parts and elements can be variously arranged and organized without departing from the spirit of this invention.

Referring to the accompanying drawings in which like reference characters indicate like parts throughout:

Figure 1 is a perspective view of a pop-up toy embodying the present invention; the toy being shown in open position, that is, with the pop-up element protruding from the case or housing.

Figure 2 is a view, partly in vertical section and partly in elevation, of the embodiment of Fig. 1; showing the appearance of the toy in closed position, with the pop-up element locked in place.

Figure 3 is a view of the toy in closed position, partly in section and partly in elevation, but at an angle of 90 degrees from the view of Fig. 2.

Figure 4 is an enlarged elevational view of the lid locking structure, locking generally in the direction of the arrows 4—4 in Fig. 2.

Figure 5 is a cross-sectional view taken generally along the line 5—5 of Fig. 2; the normal circular locking position of the housing aperture or mouth being shown in solid lines while the manually distorted generally oval release position is shown in dash-dot lines.

According to the embodiment of Figs. 1—5, I may pro-

2

vide a jack-in-box pop-up toy including a hollow housing 10 which is preferably molded or otherwise appropriately formed of any suitable material capable of being temporarily deformed when manually squeezed and of returning to its original shape when released. I have found that the relatively soft but form-retaining and somewhat resilient synthetic resins, such as styrene, are particularly well suited for this purpose although rubber (of an appropriate degree of softness) or other suitable material can be used.

The housing 10 may be molded so as to have the external appearance of a piece of fruit, for example an apple, although the ornamental appearance of the toy is not part of this invention.

A normally circular opening or mouth 12 is formed at the top of the housing 10 and is provided with an integrally formed inwardly directed annular flange 14, as best shown in Figs. 1, 2, 3 and 5.

The annular flange 14 is provided with at least one pair of diametrically-opposed slots 16. In Fig. 1, there are shown two such pairs of diametrically-opposed slots 16, so that the individual slots are spaced 90 degrees apart. However, it is also possible to employ only a single pair of diametrically-opposed slots or to employ more than two such pairs of slots; as for example three pairs of slots which would provide six individual slots spaced 60 degrees apart.

The bottom 18 of the housing 10 may have a somewhat raised central portion 20 which is positioned more or less at the level of an inwardly directed annular flange 22; the central portion 20 and the annular flange 22 forming an annular compartment 24, the outer periphery of which is recessed slightly beyond the flange 22.

The pop-up element, which is indicated generally by the reference numeral 26 includes a head 28, which may be hollow and may be formed from a pair of pre-molded left and right half-sections of synthetic resin or other suitable material fastened together, for example adhesively, along a central line 30 running completely around the head.

The head 28 is shown, in Figs. 1—3, as resembling the head of a worm although, again, the ornamental appearance forms no part of the present invention.

The head includes a downwardly and outwardly tapered generally frusto-conical neck portion 32 terminating in a flat generally circular bottom wall 34. Each of the two half-sections of the bottom wall 34 is provided with an eye portion protruding downwardly at the seam or fastening line 30; the two eye portions being juxtaposed when the head half-sections are fastened together, so as to form a downwardly protruding eye 36 disposed centrally of, and parallel to, the line 30, as indicated in Figs. 2 and 3.

The head 28 is mounted upon a helical spring 40 of frusto-conical configuration; the upper smaller end of the spring bearing against the bottom wall 34 and being secured thereto by a straightened generally diametric end portion 38 which passes through the eye 36, as indicated in Figs. 2 and 3.

The lowermost turn or turns of the spring 40 are inserted into the annular compartment 24 formed at the bottom of the housing 10 by a rotating or twisting motion, so that the pop-up element is fastened to, and supported by, the bottom of the housing.

A cloth sleeve 42 preferably covers the spring 40; the

upper end of the sleeve 42 fitting over, and being fastened to, the outside of the lower neck portion 32.

Fastened to the top of the head 28 is a lid or cover 44 which may be molded or otherwise suitably formed of the same material as the housing 10, for example a synthetic resin like styrene.

The lid or cover 44 is complementary, in external appearance, to the housing 10 so that, when the lid or cover 44 is locked in place, covering the housing mouth 12, the two together give the external appearance of the complete piece of fruit. In the illustrative form shown in Figs. 1, 2 and 3, the external appearance of the lid or cover 44 is that of the top of an apple with a generally convex configuration, a central dip or hollow and a stem although, as mentioned above, the ornamental appearance or design forms no part of the present invention.

The underside of the lid 44 is provided with a downwardly directed hub 46 which is adhesively or otherwise appropriately fastened to the head 28 at a point somewhat to the rear of the central vertical axis 48 of the head; the reason for this to be brought out hereinbelow.

Extending diametrically across the underside of the lid 44, from the hub 46, is an integrally formed relatively thin strengthening rib 50 provided, at its outer ends, with downwardly projecting locking elements 52, as best shown in Figs. 1 and 2.

Each of the locking elements 52 is provided with an inwardly and downwardly inclined camming surface 54 at its lower outer edge. An inwardly directed locking notch 56 is formed in each locking element 52 at the upper end of the camming surface 54. The distance between the upper ends of the two camming surfaces 54 is slightly greater than the distance between the inner walls of any pair of the diametrically-opposed flange slots 16, whereas, the distance between the lower ends of the two camming surfaces is slightly less than the distance between the inner walls of the pair of diametrically-opposed flange slots. As indicated best in Fig. 4, the transverse dimension of each downwardly projecting locking element 52 is slightly less than the transverse dimension of the flange slots 16, so that the locking element can move vertically within the slot.

It is apparent that, if the lid 44 is so positioned relative to the mouth 12 that the projecting locking elements 52 are in line with any pair of diametrically-opposed flange slots 16, the lid can be manually depressed (compressing the spring 40) to enable the locking elements to enter, and pass downward through the slots 16. The inclined camming surfaces 54 contact the inner walls of the slots 16 and momentarily force them apart enabling the upper ends of the camming surfaces to pass downward beyond the slots until the rim of the lid or cover seats itself upon the mouth flange 14, as indicated in Fig. 2.

In this position, the underlying locking elements 52 maintain the lid 44 in position upon the housing 10 with the spring 40 compressed.

Due to the fact that the hub 46 of the lid 44 is fastened to the head 28 at a point somewhat removed from the head axis line 48, the head 28 is tilted somewhat from the vertical when the lid is locked to the housing 10, as shown in Fig. 3. This results in a corresponding displacement of the spring axis line 58 from the vertical so that the two axis lines 48 and 52 are at a substantial angle to each other when the lid 44 and the pop-up element 26 are in the closed position of Figs. 2 and 3.

The manner of operating the toy is best indicated in Fig. 5 wherein the normal circular locked position of the housing mouth 12 is shown in solid lines. When the housing 10 is squeezed by the user's fingers, at more or less diametric points which are appreciably angularly displaced from the line of the rib 50, the pressure causes temporary deformation of the housing and changes the configuration of the housing mouth 12 to a generally oval shape, as indicated in dash-dot lines in Fig. 5.

Since the pair of flange slots 16 with which the locking

elements 52 are engaged are located more or less along the major axis of the oval configuration of the housing mouth 12, they are now spaced apart a distance somewhat greater than the distance between the outer edges of the two locking shoulders 60 formed by the notches 56.

As a result, the lid 44 and the head 28 are free to jump upward, under the action of the compressed spring 40, to the protruding or open position shown in Fig. 1.

Due to the angular displacement of the head axis line 48 and the spring axis line 58, the sudden upward movement of the pop-up element 26 is accompanied by a gyrating or twisting movement so that the element 26 continues to vibrate or rock vigorously back and forth for an appreciable time after the pop-up element 26 is released.

This provides an amusing and interest-attracting action for a child.

The extent of the gyrating action is increased by reason of the added weight provided at the top of the pop-up element 26 by the lid 44.

Since the lid is fastened to the head slightly behind the axis line 48, it tends to tilt the pop-up element 26 backwards slightly, when in open position, so as to make the face of the head 28 more easily visible, as illustrated in Fig. 1.

Since the pop-up element 26 is mounted on the spring 40, the lid can be readily rotated to fit into any of the pairs of diametrically-opposed flange slots 16 for easy re-locking.

The novel pop-up toy of the present invention can be fabricated easily and inexpensively and is durable and long-lasting; the use of strong shock-absorbing material like styrene enabling it to withstand the punishment to which children's toys are subjected.

The present invention may be embodied in other specific forms, and therefore, the above-described embodiment is to be considered in all respects merely as illustrative and not restrictive; reference being made to the appended claim as indicating the true scope of this invention.

Having thus described my invention, I claim as new and desire to protect by Letters Patent the following:

A children's pop-up toy comprising a generally hollow housing formed of somewhat soft and resilient manually deformable non-metallic material, said housing having an upper normally circular mouth which is provided with an inwardly directed annular flange, said mouth flange being provided with a plurality of uniformly circumferentially spaced pairs of diametrically-opposed slots, a pop-up element including a compression spring and a head or the like mounted at the upper end of said spring, fastening means for securing the lower end of the spring to the inner bottom of said housing, a lid or cover mounted upon the head and constructed and arranged to fit snugly upon and to cover said mouth, and releasable locking means for causing locking engagement of the rim of said lid with the edge of said mouth at one or more points when said lid is manually forced downward to move the pop-up element from partially upwardly protruding spring-extended position to fully enclosed spring-compressed position within the housing, said locking means comprising a pair of diametrically-opposed downwardly protruding elements each having a shoulder constructed and arranged to underlie and engage the juxtaposed portion of the flange when the lid is seated upon said mouth flange, the outer ends of the locking shoulders underlying the inner walls of the flange slots, said locking elements passing through the diametrically-opposed slots in the annular flange when moving downwardly to engaging position, the lower outer ends of the locking elements being provided with downwardly and inwardly inclined camming surfaces constructed and arranged to contact and momentarily displace the inner walls of the slots to facilitate engagement of the locking elements, the locking elements being provided with

notches extending inwardly from their outer walls generally at the upper ends of the camming surfaces, the notches engaging the flange slots to prevent rotational shifting of the locked lid and pop-up element, squeezing pressure upon the housing at points below the mouth opening and appreciably displaced from the line of the two locking elements causing ovalizing distortion of the mouth sufficient to shift the engaged portions of the flange away from the locking element shoulders so as to effect release of the pop-up element and lid, thereby enabling the pop-up element and lid to jump up suddenly under the pressure of the compressed spring, the plurality of uniformly circumferentially spaced pairs of diametri-

cally opposed slots permitting the lid and pop-up element to be engaged in different rotationally spaced positions relative to the mouth, thereby causing displacement of the compressed spring and subsequent gyration upon release of the pop-up element.
